UNITED STATES PATENT OFFICE.

FRANK J. ROETKER, OF MOFFAT, COLORADO.

PENCIL-TOP.

1,211,356.

Specification of Letters Patent.

Patented Jan. 2, 1917.

Application filed February 25, 1916. Serial No. 80,461.

To all whom it may concern:

Be it known that I, FRANK J. ROETKER, a citizen of the United States, residing at Moffat, in the county of Saguache and 5 State of Colorado, have invented new and useful Improvements in Pencil-Tops, of which the following is a specification.

This invention relates to an attachment 10 for pencils and has for its primary object to provide an attachment by means of which suitable indicating and advertising means may be supported upon a pencil.

An object of the invention is to provide 15 a device for supporting indicating or advertising means upon a pencil in such a position as to be readily viewed by the writer.

Another object of this invention is to provide 20 an attachment so constructed as to detachably support indicating or advertising means or both.

With these and other objects in view, the invention consists in the construction and arrangement of parts as will be hereinafter 25 more fully described, illustrated in the accompanying drawings and pointed out in the claim hereunto appended.

In the drawings:—Figure 1 is a perspective 30 view of the attachment shown applied to a pencil. Fig. 2 is a view on an enlarged scale. Fig. 3 is a vertical sectional view. Fig. 4 is a horizontal sectional view.

Referring to the drawing, the numeral 1 35 designates a pencil to one end of which is applied the attachment 2.

At the start, I wish it to be understood that although the attachment is shown applied to the usual rubber end of the pencil, I wish it to be understood that the same 40 may be applied to the sharpened end of the pencil so as to protect the point during the idle periods of the pencil.

The attachment comprises a casing 3 having 45 a partition dividing the interior of the casing into a card compartment and a compartment 11 that receives one end of the pencil. A slot 4 is formed in two opposite

side walls 5 and 6 of the card compartment, the slot extending through one end of the casing. In this particular instance I have 50 shown slidably mounted in the card compartment a plurality of cards 7 all of which with the exception of an end card has printed thereon the days of the month. This mentioned end card 8 has printed thereon 55 any suitable advertisement.

For preventing displacement of the cards, I provide a cap 9 completely inclosing one end of the casing which is provided with inclosed slots as indicated at 10. From this 60 arrangement it will be seen that the walls of the card compartment are prevented from bending out of place, while at the same time any suitable indicia upon the cards may be visible through the slots 10. 65

From the foregoing description taken in connection with the accompanying drawing, it should be apparent that I provide a device which is admirably adapted for the purpose for which it is intended, that the 70 device is simple, durable and efficient of construction, and that the device may be manufactured and sold at a comparatively low cost.

What I claim is:—

A pencil attachment comprising a plurality of indicating cards, a casing having a partition dividing the interior thereof into two compartments one of rectangular configuration for receiving said cards, the 80 other receiving one end of the pencil, two opposite walls of said card compartment being formed with slots extending through one end of the casing, and a cap completely inclosing the card end of the casing and 85 having inclosed slots arranged parallel to portions of the slots in said side walls.

In testimony whereof I affix my signature in presence of two witnesses.

FRANK J. ROETKER.
